[57] CLAIM

The ornamental design for an exterior lamp, as shown and described.

DESCRIPTION

FIG. 1 is a front perspective view of an exterior lamp showing our new design;

FIG. 2 is a front elevational view thereof;

FIG. 3 is a right side elevational view thereof, the left side being a mirror image;

FIG. 4 is a top plan view thereof;

FIG. 5 is a bottom plan view thereof; and,

FIG. 6 is a rear elevational view thereof.

The broken line showings of the light bulb sockets in FIG. 1, the tail in FIGS. 1, 2, 3, 5 and 6 and of the base in FIGS. 1, 2, 3, 5 and 6 are for purposes of illustration only and form no part of the claimed design.
